(57) **CLAIM**

The ornamental design for a protective battery case for mobile communications device, as shown and described.

DESCRIPTION

FIG. 1 is a bottom-front perspective view of the design for a protective battery case for mobile communications device; FIG. 2 is a top-rear perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

The broken lines and regions bounded by broken lines form no part of the claimed design.
